UNITED STATES PATENT OFFICE.

JAMES A. EDEN, JR., OF SPRINGFIELD, MASSACHUSETTS, ASSIGNOR TO WALTER H. FOSTER, OF NEW YORK, N. Y.

MACHINE FOR THREADING BUTTON-HEAD STAYBOLTS.

1,322,885.

Specification of Letters Patent. Patented Nov. 25, 1919.

Application filed March 6, 1918, Serial No. 220,719. Renewed April 5, 1919. Serial No. 287,924.

To all whom it may concern:

Be it known that I, JAMES A. EDEN, Jr., a citizen of the United States, residing in Springfield, Massachusetts, have invented 5 certain new and useful Improvements in Machines for Threading Button-Head Staybolts, of which the following is a specification.

This invention aims to provide a machine 10 for controlling the operation of the threading devices in machines for making staybolts of certain types.

The accompanying drawings illustrate an embodiment of the invention.

15 Figure 1 is a side elevation of the carriage of a staybolt machine and related parts;

Fig. 2 is a plan and Fig. 3 a section of a detail on the line 3—3 of Fig. 2.

20 Fig. 4 is an underside plan view of the chasers or cutters and their operating mechanism.

The carriage A slides up and down in suitable guides. On the underside of the 25 carriage is a plate B which carries the dies or chasers which are to operate on the blank or bolt indicated at C. These chasers are moved inward to close them on the work or outward to release them by the turning of a 30 ring D mounted to rotate on the plate B. Springs are provided to turn the ring D in the direction of the arrow. The usual operation is as follows:

The carriage is held in an upper position 35 at which point the ring D is turned to the relative position here illustrated and a stop E thereon is caught by a pawl F so that the ring is held and the dies are held in the closed position. The die head is allowed to 40 rest by gravity on the top of the bolt and the latter is turned. The dies cut the required thread on the bolt and the die-head and carriage move down as the thread is cut toward the lower end. The lower squared 45 end of the blank rests in the socket in a block G which is continuously rotated so as to give the required rotation to the work.

A head or "button-head" H as it is sometimes called is provided on the lower end of 50 the blank with a squared extension H' which rests in the socketed block G and determines

the height at which the blank stands, and which after the bolt is in use is generally cut or twisted off to leave only the button head. It is desirable that the thread be cut 55 clear to the face of the head H. The usual practice is to automatically lift the pawl F and release the ring D to open the cutters at a predetermined point in the downward movement of the carriage, this being calculated as nearly as possible to stop the thread 60 close to the head of the blank. The blank however is a casting and the head H and extension H' are formed by upsetting and are sometimes quite irregular in shape. And 65 the heads of the different blanks are not always of the same dimensions. It follows that sometimes the thread is stopped before being cut quite to the head. At other times, the thread runs too long, and the dies dig 70 into the shoulder or face of the head with consequent injury to the thread and to the dies.

I have provided a device whereby the 75 opening of the dies or the cutting of the thread is stopped under control of the head itself so that for a thicker head the thread will stop earlier and for a thinner head later, and can be calculated to run exactly 80 to the shoulder and not farther without regard to variations between different bolts. For this purpose I control the movement of the pawl F and the opening of the dies by the shoulder itself on the work.

The pawl F is connected by a link J to an 85 arm K on a shaft L mounted on the carriage, and carries an inner arm M in the end of which is mounted a rod N which extends down through the carriage and the cutter head and has its lower end close alongside 90 the body of the blank and projecting slightly below the cutter head.

Near the end of the downward threading movement of the carriage, the lower end of the rod N will strike on the shoulder of the head H and as the downward movement continues the rod N will be lifted and the lever arms K and M will swing upward at their ends, pulling up the link J and pawl F. As soon as the latter rises sufficiently the 100 stop E and ring D will be released and the usual springs will throw it around and

open the dies so as to stop the cutting operation. The die head with its open chasers will then be free to drop and will come to rest on the top face of the bolt head; which thus serves to terminate not only the thread but also the feeding operation of the machine.

For accommodating the machine to bolts of different diameters, or with heads or shoulders of different widths, the arm M 10 may be made adjustable on the shaft L so as to move toward or from the center of the blank. For this purpose, as shown in Fig. 3, the arm M is split and clamped on the shaft 15 L by means of a clamping screw O. Loosening this screw permits the desired adjustment, and after adjustment the screw can be easily tightened to hold the arm in place.

Fig. 4 shows the details of the dies or 20 chasers and the operating mechanism therefor. Each of the cutters P is mounted in a bracket Q which is pivoted at R to the underside of the plate B, Fig. 1. Surrounding these is a ring D. Toggle links S engage 25 sockets in said ring and in the respective brackets Q which carry the cutters. Springs T are connected at one end to the underside of the carriage A and at their opposite end to the ring D so as to turn the latter in the 30 direction of the arrow when it is released in the manner explained above.

The die head illustrated is more fully described and is claimed in my co-pending application No. 220,718 filed March 6, 1918.

35 Though I have described with great particularity of detail a specific embodiment of my invention, yet it is not to be understood therefrom that the invention is restricted to the particular embodiment disclosed. Various 40 modifications thereof in detail and in the arrangement of the parts may be made by those skilled in the art without departure from the invention as defined in the following claims.

45 What I claim is:—

1. A machine for threading button head stay bolts including in combination a rotating socketed block adapted to receive a squared extension of the head of the blank 50 and to support the blank at a fixed height and to rotate it, a die head adapted to travel downward by gravity and thus to cut a thread on said blank, said die head carrying chasers arranged to spring open just suffi- 55 ciently to clear the threaded portion but not to clear the head and carrying a latch for holding the chasers closed, and a latch-withdrawing device carried also by said die head, moving down with the die head and 60 located in position to strike the upper face of the head of the blank and to be moved upward thereby to withdraw the latch, whereby the thread is terminated and the die head with its open chasers may drop

freely and come to rest on the top face of 65 the bolt head and thus also terminate the feed.

2. A machine for threading button head stay bolts including in combination a rotating socketed block adapted to receive a squared extension on the head of the blank 70 and to support the blank at a fixed height and to rotate it, a die head adapted to travel downward by gravity and thus to cut a 75 thread on said blank, said die head carrying chasers arranged to spring open and carrying a latch for holding them closed and a rod arranged to withdraw said latch extending downward through said die head, moving down therewith and having its lower 80 end located in position to strike directly on the upper face of the head of the blank and to be moved upward thereby to withdraw the latch and to remain in engagement with said head during the continued down- 85 ward movement, whereby the thread is terminated and the die head with its open chasers may drop freely and come to rest on the top face of the bolt head and thus also terminate the feed, said rod having a simple 90 vertical reciprocating movement so that when the die head is raised it will be automatically lowered to its starting position.

3. A machine for threading button head stay bolts including in combination a rotating socketed block adapted to receive a squared extension of the head of the blank 95 and to support the blank at a fixed height and to rotate it, a die head adapted to travel downward by gravity and thus to cut a thread 100 on said blank, said die head carrying chasers arranged to spring open just sufficiently to clear the threaded portion but not to clear the head and carrying a latch for holding the chasers closed and a rod arranged to 105 withdraw said latch extending downward through said die head, moving down therewith and having its lower end located in position to strike directly on the upper face of the head of the blank and to be moved upward thereby to withdraw the latch and to remain in engagement with said head during the continued downward movement, whereby the thread is terminated and the die head with its open chasers may drop 110 freely and come to rest on the top face of the bolt head and thus also terminate the feed, said rod having a simple vertical re- 115 ciprocating movement so that when the die head is raised it will be automatically low- 120 ered to its starting position and being adjustable toward and away from the center of the bolt to adapt it to operate with bolts of different dimensions.

4. A machine for threading shouldered or 125 headed bolts including in combination thread cutting dies, a die holder and a bolt-holder, one of said holders having a reciprocating

movement with relation to the other in a direction parallel to the axis of the bolt to carry the dies toward and away from the head of the bolt, means for holding said dies closed to cut a thread as they approach the shoulder on the bolt and means controlled by such shoulder for causing an

opening of the dies just before they reach it so that the dies on their backward movement will clear the portion of the bolt 10 threaded on its forward movement.

In witness whereof, I have hereunto signed my name.

JAMES A. EDEN, JR.
